UNITED STATES PATENT OFFICE

SOLOMON H. GOLDBERG, OF CHICAGO, ILLINOIS, ASSIGNOR, BY MESNE ASSIGNMENTS,
TO CHAIN STORE PRODUCTS CORPORATION, OF CHICAGO, ILLINOIS, A CORPORATION
OF DELAWARE

DESIGN FOR A PACKAGE OR SIMILAR ARTICLE

Application filed May 2, 1930. Serial No. 35,483. Term of patent 14 years.

To all whom it may concern:

Be it known that I, SOLOMON H. GOLDBERG, a citizen of the United States, residing in the city of Chicago, county of Cook, and State of Illinois, have invented a new, original, and ornamental Design for a Package or Similar Article, of which the following is a specification, reference being had to the accompanying drawing, forming part hereof, in which—

Fig. 1 represents a perspective view of the article, showing my design, and Fig. 2 is a perspective similar to Fig. 1, with the cover open.

I claim:

The ornamental design for a package or similar article, as shown.

SOLOMON H. GOLDBERG.
